KENNETH P. ROLSTON, OF PITTSBURGH, PENNSYLVANIA, ASSIGNOR TO R. E. TONGUE & BROTHERS COMPANY, INC., OF PHILADELPHIA, PENNSYLVANIA, A CORPORATION OF PENNSYLVANIA

CRIMPING MECHANISM

Application filed April 23, 1929. Serial No. 357,420.

The present invention relates to crimping devices and more particularly to a mechanism for crimping the end of a lamp chimney.

5 Some of the objects of the present invention are to provide an improved device for crimping the top marginal edge of a lamp chimney; to provide a device for forming a bead or rim on a lamp chimney of a thickness 10 greater than the thickness of the glass of the body of the chimney; to provide a device for forming a bead on a lamp chimney and simultaneously shaping the bead with a scalloped contour; to provide a device which 15 forms a thick bead, scallops the bead, and externally flutes the bead in one operation; to provide a crimping device having removable interchangeable shaping dies; to provide means for interlocking a shaping die in 20 a crimping head; and to provide other improvements as will hereinafter appear.

In the accompanying drawings Fig. 1 represents a plan of a crimping mold embodying one form of the present invention; Fig. 2 represents a section on line 2—2 of Fig. 1 showing the rotatable plug in side elevation; Fig. 3 represents a section of the plug on line 3—3 of Fig. 2; and Fig. 4 represents a side elevation in part section of a lamp chimney 30 top as formed by the crimping mold.

Referring to the drawings one form of the present invention consists of a crimping body 10, preferably of steel, terminating at one side in an annular flange 11, and at the 35 opposite side in a tubular hub or shank 12 concentric with respect to the flange 11. The flange 11 forms and encircles a cylindrical opening 13, the bottom of which is formed by the reduced diameter of the shank 12, while 40 the depth of the opening 13 is such as to receive the end of the lamp chimney to be crimped as well as certain of the forming adjuncts.

In order to provide the upper marginal 45 edge of the lamp chimney with an external circumferential fluting, the flutes of which are parallel to the long axis of the chimney, the internal circumferential face of the flange 11 is milled or otherwise cut with coaxial teeth 14 of such configuration as will

provide a longitudinal groove between each pair of teeth of the desired shape to produce the predetermined contour of molded flute 15. The formation of these teeth 14 is facilitated by the provision of an internal circumferential groove 16 which is spaced from the outer face of the flange 11 the necessary distance to allow the teeth to have the desired length.

For the purpose of forming a scalloped face on the end of the lamp chimney, a ring 17, preferably of bronze, is arranged to fit within the opening 13 and seat flush against the bottom thereof. The outside diameter of this ring 17 is such that it fits snugly within the internal diameter of the flange 11 but can be readily removed therefrom when required. The outer face of the ring 17 is of the scalloped shape desired to produce the finished contour of the lamp chimney end and, as here shown, consists of a plurality of 55 arched depressions 18 so spaced as to form relatively long curved projections 20 between the pairs of depressions respectively. These projections 20 mold into the chimney end corresponding long deep recesses 21 which serve 60 as lateral air passages in the finished lamp chimney. The axial length of the ring 17 is less than the length of the opening 13 so that a rim 22 of desired length can be molded. Also the thickness of the ring 17 is such as to 65 increase the normal thickness of the chimney and thus form a relatively thick top marginal edge upon the chimney.

For fastening the ring 17 in position so that it cannot turn relative to the flange 11 it is provided at one or more locations with a slot or slots 23 for the reception of a screw or screws 24 which thread through the head at convenient points to enter the slots 23. This not only holds the ring 17 in place but provides a means whereby the ring can be 70 taken out and quickly replaced by another say for example one having a scallop or other form of different design.

As a means for internally shaping the 75 throat and mouth of the chimney while working the molten glass into the crimped condition, a plug body 25 is provided having a stem 26 extending axially through the shank 12 for attachment to the rotatable and recip-

roable spindle of the crimping machine. The plug body 25 is cylindrical and has a diameter slightly less than the internal diameter of the ring 17 to allow unrestricted relative turning movement of the plug. Coaxial 5 with the stem 26 but projecting from the opposite side of the plug body 25 is an elongated tool 27 of a length and size to enter the end of the lamp chimney when the latter is in the crimping head. As here shown, the tool 27 10 has four inwardly curved or concave sides 28 which converge to a common point in the nose 30 of the extension, thereby forming a relatively long tapered shaping member having 15 a plurality of well defined working edges 31. Thus in assembled condition the plug body 25 fits within the ring 17 and is free to move axially relatively thereto as well as having a rotary motion about its own axis 20 so that the projecting tool 27 can perform its shaping function within the end of the lamp chimney.

In operating the crimping device the end 25 to the necessary temperature to give the desired ductility and it is then pressed into the opening 13 against the stationary ring 17 so that the glass fills the scalloped depressions therein. Simultaneously the plug body 30 25 is advanced, while rotating towards and into the heated glass to thereby form an inner wall spaced from the inner circumferential face of the flange 11, so that as the glass is pressed into the body 10 it will be forced 35 laterally into the die formed by the teeth 14. While this rim crimping operation is taking place the tool 26 is shaping the throat and rim flare of the chimney as will be seen from Fig. 4.

40 It will now be apparent that a complete unitary crimping device for lamp chimneys has been devised wherein a head or rim is formed on the end of a chimney simultaneously with the formation of a scallop thereby providing a circumferential top margin 45 of increased thickness capable of resisting breakage. Also the scalloping of this heavy rim or bead provides a plurality of relatively large lateral passages for air and products 50 of combustion which come into operation when a container is placed upon and closes the normally open top of the chimney. Furthermore, the present construction makes possible the use of various shaped scalloped 55 die rings since one can be readily substituted for another without interfering with the other parts of the crimping head.

Having thus described my invention, I claim:

60 1. A crimping device comprising in combination a head having a material receiving opening and provided with an internally toothed circumferential face encircling said opening, a shaping die ring in said opening 65 juxtaposed in close proximity to a portion of

said face, and a rotatable tool arranged to operate through said ring to engage said material for crimping and shaping action whereby a scalloped top edge having a corrugated outer face is formed upon an article 70 molded in said head.

2. A crimping device comprising in combination a head having a material receiving opening and provided with an internally toothed circumferential face encircling said opening, and means including a scalloped die ring for simultaneously crimping said material against said face and forming a scalloped edge of greater thickness than the body of 75 said material.

Signed at Pittsburgh, county of Allegheny, State of Pennsylvania, this 19th day of April, 1929.

KENNETH P. ROLSTON.
